UNITED STATES PATENT OFFICE.

MARCUS J. CARLS AND HENRY F. PRUCHA, OF LOS ANGELES, CALIFORNIA.

DESIGN FOR A CHILD'S CART.

55,743.

Specification for Design.

Patented July 13, 1920.

Application filed August 23, 1917. Serial No. 187,894. Term of patent 14 years.

To all whom it may concern:

Be it known that we, MARCUS J. CARLS and HENRY F. PRUCHA, both citizens of the United States, residing at the city of Los Angeles, county of Los Angeles, State of California, have invented a new, original, and ornamental Design for a Child's Cart, of which the following is a specification, reference being had to the accompanying drawings, forming a part thereof.

The figure is a perspective view of a child's cart showing our new design.

The object of our invention is to provide a child's cart that will resemble an aeroplane.

Referring to the drawing, the front frame of the child's cart represents the main planes of an aeroplane and is composed of upper and lower boards held together by the end posts. Legs are secured to the lower board and a front axle is revolubly mounted therein. Front wheels are rigidly secured to the front axle and a grooved pulley is also se-

cured thereon. A cord passes over the pulley on the front axle and over a grooved shaft revolubly mounted in a brace secured to the boards of the front frame. The upper board has hand holes therein for the reception of the hands to guide the child's cart. Pivotaly secured to the boards of the front frame by a bolt is the rearwardly extending body member which carries the seat and ends in a tail. Rear legs are secured to the body and carry the rear axle on which are mounted the rear wheels. To the shaft mounted in the brace are secured propeller blades, and when the child's cart is moved the blades are revolved, thus producing the illusion of the cart being driven thereby.

We claim:

The ornamental design for a child's cart as shown and described.

MARCUS J. CARLS.
HENRY F. PRUCHA.
